A. J. Walker,

Hat and Coat Hook.

No 41,798.

Patented Mar. 1, 1864.

Witnessed:

Samuel H. Lovell.
John Newell.

Inventor:

Alex. J. Walker.

UNITED STATES PATENT OFFICE.

ALEXANDER J. WALKER, OF NEW YORK, N. Y.

IMPROVED WARDROBE-HOOK.

Specification forming parts of Letters Patent No. 41,798, dated March 1, 1864.

To all whom it may concern:

Be it known that I, ALEXANDER JAMES WALKER, of the city and State of New York, have invented, made, and applied to use a certain new and useful Wardrobe-Hook; and I do hereby declare the following to be a full, clear, and exact description of the said invention, reference being had to the annexed drawing, making part of this specification, wherein—

Figure 1 is a side elevation of said hook. Fig. 2 is a front elevation of the same, and Fig. 3 is another form of constructing the eye of the hook.

Similar marks of reference denote the same parts.

Metallic hooks for hanging clothing upon in wardrobes, closets, &c., are usually constructed in such a manner that they can be used only by fastening them permanently in place by means of screws or nails, and can be taken down again only by withdrawing the screws or nails. This is a troublesome process, requiring a certain amount of mechanical skill, and often resulting in injury to the wall or other article to which the hooks are attached, and sometimes in the breakage of the hook. They are also liable to be drawn out of place by the weight put upon them.

The nature of my invention consists in a pendent wardrobe-hook formed with an eye, by which it can be suspended for use from a nail, screw, or other device, said hook being a new article of manufacture, portable, easily put up and taken down, and not liable to break the nail or screw in consequence of leverage.

In the drawings, a is the back part of my hook, formed with an eye, c, at the upper end, and with arms b b extending out from the same, upon which the articles of clothing are to be hung. These arms may be of any desired number.

It will be evident that the hook, hanging from the eye c, with the part a against the wall or place to which the hook is applied, will sustain such articles as may be hung upon it without liability to change its position.

A hook of this character has many advantages. It is very quickly and easily put up for use, as any one, even a child, however unskilled, can drive a nail, which is all that is required. Opportunities, too, of inserting a nail often exists under circumstances where a wardrobe-hook of the ordinary construction could not be secured. It is especially convenient for travelers, as it is portable, and can be quickly hung up and taken down at pleasure, and it can under all circumstances be removed without any injury to the wall or furniture, the nail or screw alone remaining.

What I claim, and desire to secure by Letters Patent, is—

The pendent wardrobe-hook constructed substantially as and for the purposes specified.

Dated December 24, 1863.

Witnesses: ALEX. J. WALKER.

LEMUEL W. SERRELL,
CHAS. H. SMITH.